P. Boisset

UNITED STATES PATENT OFFICE.

PIERRE BOISSET, OF PARIS, FRANCE, ASSIGNOR TO HIMSELF AND BERNARDO ANTOGNINI.

IMPROVEMENT IN BOOTS OR SHOES.

Specification forming part of Letters Patent No. 35,057, dated April 22, 1862.

To all whom it may concern:

Be it known that I, PIERRE BOISSET, of Paris, in the Empire of France, have invented a new and useful Improvement in Boots or Shoes; and I do hereby declare that the following is a full and exact description of the same, reference being had to the accompanying drawings, and to the letters of reference marked thereon.

Figure I represents a top view of a shoe or boot sole, and Fig. II is a section of the same.

The nature of my invention consists in the combination, with caoutchouc soles for boots or shoes, of a metal piece or pieces pierced with a suitable thread-hole for the reception of screws by which the upper-leather and inner soles are securely fastened to the caoutchouc soles.

In the application of india-rubber or gutta-percha soles as a substitute for leather soles to boots or shoes the greatest difficulty has existed heretofore in attaching said soles firmly to the upper-leather or vamps. Screws have been used for this purpose, but from the nature of the caoutchouc it is very difficult to make the thread of the screws hold firmly in this material, and after a very little use the screw will easily pull out of the same.

In the accompanying drawings, A represents the shank and heel of a sole made of caoutchouc, on the forward end of which a leather sole, B, may be attached, or the whole sole may be made of caoutchouc, if desirable. C represents the upper-leather or vamps, which is turned in between the outer or caoutchouc sole, A, and the inner sole, D.

In the caoutchouc sole A small metal pieces a are incorporated during the process of making said sole. These metal pieces a are provided with a suitable hole in which a screw-

thread is cut corresponding with the thread of the screws to be used.

The inner sole, D, and the upper-leather C are attached to the caoutchouc sole A by means of any desired number of screws s, screwed through that part of the caoutchouc situated above the metal pieces and then into these metal pieces a, by which the screws will be prevented from pulling out, and which will hold the same firm and fast, similar to a nut.

Instead of small metal pieces being incorporated with the sole, as above described, a plate provided with the desired number of holes with screw-threads cut in may be incorporated therein; but I prefer the use of small pieces, as the weight is thereby not considerably increased.

I am aware that screws have been used before for the purpose attaching the inner sole and upper-leather to the outer soles made of caoutchouc or its equivalent, said screws having been screwed into the sole, and do therefore not claim the use of screws for the purpose of attaching the upper-leather to caoutchouc soles; but

What I claim as my invention, and desire to secure by Letters Patent, is—

The combination, with a plate or nut, a, when the same is embedded or incorporated within the india-rubber or caoutchouc sole while being made, of a screw so arranged and operating in connection with said plate as to allow of the sole being screwed up and fastened to the upper-leather, substantially in the manner and for the purpose specified.

PIERRE BOISSET.
